JOHN A. HAASE, OF PHILADELPHIA, PENNSYLVANIA;

Letters Patent No. 72,028, dated December 10, 1867.

IMPROVED HOSE-SHIELD.

The Schedule referred to in these Letters Patent and making part of the same.

TO ALL WHOM IT MAY CONCERN:

Be it known that I, JOHN A. HAASE, of the city and county of Philadelphia, and State of Pennsylvania, have invented a new and useful Improvement in Hose-Shields; and I do hereby declare that the following is a full and exact description thereof, reference being had to the accompanying drawings, and to the letters of reference marked thereon.

The nature of my invention consists of a portable hose-shield, which has a foot-way between the sectional rails, for the car-horses to walk over. The shield is constructed in sections, for convenience in handling and conveying it from one part of the city to another.

The construction and operation will be understood by the following description. In the accompanying drawings, which make a part of this specification—

Figure 1 is a plan of the improved shield.

Figure 2 is a vertical section of the same.

Figure 3 is a side elevation.

Figure 4 is a cross-section at the red line xx of fig. 1.

Like letters in all the figures indicate the same parts.

I have represented the shield as composed of three sections, so as to be conveniently handled and moved from one part of the city to another. The middle section A, and the end sections B B, are confined together by means of hooks and eyes a and a' , as represented in figs. 1 and 3. Each section has thick side pieces b b , which have grooves c c , as seen in fig. 4, to receive the edges of the floor C, which is confined between the side pieces by means of bolts passing through each, the bolts being provided with heads d and nuts e , as represented in the drawings; or the side pieces may be confined to the edges of the floor by means of nails or screws. There are cross-pieces f beneath the floor, which give support to it. On the upper side there are cleats, g , which prevent the slipping of the feet of the car-horses as the latter pass over this sectional road. The side pieces b b of each section have cross-grooves, h , through their bottom edges, for hose to pass through, there being any convenient number, in accommodation to different hose companies. There are rebates i i in the lower edges of said side pieces, as seen in figs. 3 and 4, which rest upon the rails of the railway, to give lateral support to the shield. The object of the floor C is to protect the hose from the feet of the horses, and to receive the weight of the latter, to keep the shield in place.

What I claim as my invention, is—

The combination of the floor or foot-way C with the side pieces b b of a sectional hose-bridge, constructed substantially as described.

In testimony that the above is my invention, I have hereunto set my hand and affixed my seal, this ninth day of July, 1867.
